UNITED STATES PATENT OFFICE.

MARTIN B. SCHENCK, OF FULTON, NEW YORK, ASSIGNOR TO THE YALE
CASTER COMPANY, OF NEW HAVEN, CONNECTICUT.

CASTER.

SPECIFICATION forming part of Letters Patent No. 301,835, dated July 8, 1884.

Application filed September 30, 1882. (No model.)

To all whom it may concern:

Be it known that I, MARTIN B. SCHENCK, a citizen of the United States, residing at Fulton, in the county of Oswego and State of New York, have invented certain new and useful Improvements on Casters, of which the following is a specification.

My improvement relates to those casters having two floor-wheels, which are constructed to allow both a horizontal pivoting and a vertical rocking movement to the wheel frame or housing. It has been customary to pivot the housing on a central vertical pin in various manners, to allow of the rocking motion of the housing, and to journal an anti-friction wheel in the housing above the floor-wheel axle, in such manner that it will bear on the under side of a track-plate affixed to the furniture or truck, to receive a portion of the weight and serve as a rocker-bearing. With a caster thus constructed it is essential that the point of contact of the anti-friction wheel be directly above the axle of the floor-wheels. If inside of a vertical plane including this axle, a too heavy, or possibly a breaking, strain will be applied to the central pivot-pin, while if without this plane great friction would be caused both at the central pivot and at the tail-piece of the housing, and even with the anti-friction wheel placed directly above the floor-wheel axle great friction and imperfect pivoting are caused by the abutting of this tail-piece against the track-plate, especially when the caster happens to be pushed the wrong way.

My improvement relates, first, to means of overcoming this difficulty and producing at the same time a practically frictionless and a perfect oscillatory bearing for the wheel-housing. This object I accomplish by placing on one or the other side of the central pivot an additional anti-friction wheel or roller having its axis lying in a vertical plane, in which lie also the first anti-friction roller and the vertical pivot-pin.

My invention relates, secondly, to details of construction of means for accomplishing the result above set out; and, thirdly, to an improved method of connecting the pivot-pin to the housing by means of an oscillating thimble, in manner hereinafter more fully set forth,

which portion of my invention is equally applicable to a caster with one as to one with two anti-friction rollers.

In order that my invention may be fully understood, I will proceed to describe it with reference to the accompanying drawings, in which—

Figure 1 is a rear elevation of my improved caster. Fig. 2 is a side elevation of the preferred form thereof. Fig. 3 is a vertical longitudinal section of the same on the line 3 3, Fig. 1. Fig. 4 is a plan with the track-plate removed. Fig. 5 is a section, similar to Fig. 3, of a modification of my invention. Fig. 6 is a plan of the same, with the track-plate removed. Figs. 7 and 8 represent in section other modifications of my invention.

In the drawings, A is a track-plate, having means of attachment beneath a truck or piece of furniture. On the upper side of this plate is a stud or boss, a, extending into a socket in the furniture-leg or truck-bottom. On its lower side the plate bears a similar stud, a', which may, as shown in Fig. 3, extend low enough to transmit strain from the track-plate to the wheel-frame, or may, as shown in Fig. 7, be made only of sufficient depth to strengthen the central pivot-pin, by which, in this case, the whole of the strain is received and transmitted.

Passing vertically through the center of the studs a a' is a screw bolt or pin, B, having, in the form of my invention here shown, a conical head, b, which occupies a similarly-shaped hole in a washer, C. The upper end of pin B is riveted or secured by other suitable means, D, above the stud a, and the washer C is made to bear with friction against the base of the stud a', and serve as a flange to retain the thimble E in place thereon.

It will be readily seen that the form of the head b and of the hole in washer C may be altered, or that the washer may be altogether omitted, the head b being in such case flat and of sufficient width to extend beyond the stud a'. The thimble E is an oval-shaped casting having a vertical circular hole, through which passes the cylindrical stud a'. Downwardly-projecting lugs e e on the thimble have holes, through which passes loosely the hori-

zontal pin F, which enters also corresponding holes in the housing G, and serves to fasten the same to the thimble, and through it to the track-plate. A flange, e', on the thimble E, 5 assisted by the washer C, serves to retain the thimble upon the stud a', which is made of sufficient depth to allow a slight vertical play to the thimble. The housing G is provided with a recess or basin, g, for receiving the 10 thimble E and its appurtenances, and also with slots or recesses g', in the form of my invention here shown—one on each side of the recess g—so that the anti-friction wheels H H', contained in said slots, may be both journaled 15 upon the same horizontal pin, F, employed to connect the thimble and housing together. Instead, however, of having the anti-friction wheels on opposite sides of the central pivot, they may both be upon the same side; or I may 20 employ a two-faced wheel, as shown in Fig. 8 at H", to give a bearing in two places on two tracks. The anti-friction wheels H H' H" bear upwardly against a track or tracks, h, on the under face of the plate A. The 25 housing or wheel-frame G has three brackets or lugs, G', through which passes the axle I of the two floor-wheels J J.

It will be observed that the main or all of the weight of the truck or piece of furniture 30 will be carried by the wheels H H', and by them transferred to the housing. In this manner a perfect compound rocking and pivotal motion is allowed the caster. While I have here shown the outer anti-friction wheel, H, 35 almost directly above the floor-wheel axle, yet it may be placed at some distance on either side of the axle without injuring the working of the caster. It is necessary, however, in all cases that the axis of the wheels H H' and 40 the vertical pivotal point of the caster shall lie in the same vertical plane, in order to secure a perfect oscillatory motion.

In the form of my invention which I have 45 illustrated in Figs. 5 and 6, the anti-friction wheels H and H' run on different tracks on the attaching-plate, the thimble E is omitted, and the horizontal pin passes directly through

the pivot-pin, which turns within the hole in the track-plate, and is held above by screw-bolt or by riveting and washer K L.

50

The following is claimed as new in the above-described invention:

1. In a two-wheeled caster, the combination of an oscillating wheel-frame swiveled to the attaching or track plate and two anti-friction 55 wheels, one located between the two floor-wheels, and the other on an axis in line with the first, on the opposite side of the swiveling center of the caster, as herein set forth.

2. In a two-wheeled caster, the combination, 60 with an oscillating wheel-frame swiveled to the furniture or track plate, of two vertical anti-friction wheels journaled on the wheel-frame, one wheel on each side of the vertical plane of the floor-wheel axis, in the same vertical plane with the swiveling center of said frame, and both serving as bearings for oscillation, as set forth.

3. A caster consisting of two floor-wheels, 70 their bearing-frame or housing, a pivot-pin for connecting housing to track-plate, two anti-friction wheels or rollers in line with the pivotal point, and a horizontal connecting-pin passing through both anti-friction wheels and central pivot, as set forth.

4. In a two-wheeled caster, the combination of the housing having the central bowl or recess, the rocking thimble within the said bowl, anti-friction wheel or wheels, and pivot-pin having a head held and turning within the 80 said thimble, as and for the purposes set forth.

5. In a two-wheeled caster, the combination of recessed wheel-housing, rocking thimble within said recess, anti-friction wheel or wheels, swivel-pin passing through both thimble and wheel or wheels, and pivot-pin having a head within said thimble, and serving to unite the caster to the track-plate, as set forth.

M. B. SCHENCK.
